SINKER-HEAD STRUCTURE FOR KNITTING MACHINES

William E. Sheeler, Wyomissing, Pa., assignor, by mesne assignments, to Textile Machine Works, Wyomissing, Pa., a corporation of Pennsylvania

Application February 10, 1953, Serial No. 336,097

7 Claims. (Cl. 66—98)

The present invention relates to the sinker-head structure of full-fashioned knitting machines and more particularly to the needle beard pressing surface of such sinker-head structure. The instant application is a continuation-in-part with respect to all common subject matter of my co-pending application Serial No. 242,446, filed August 18, 1951, now abandoned.

As is well known, the full-fashioned type of knitting machine employs spring bearded needles which contact a presser edge portion of a sinker-head during the down or beard closing stroke in the knitting cycle of each course. The beards of the needles, being relatively harder than the presser edge and having only point contact therewith during the beard closing action, cause considerable wear in the presser edge, wearing of the presser edge and of the needle beards as well being increased by the failure to secure adequate lubrication under the high unit pressures involved. In the lower or coarser gauge machines this wear, due to the larger dimensions of the parts, was considered as inconsequential. However, as the gauge of the machines tends to be higher or finer, the wear in the presser edge caused by the smaller dimensions of the needle beards, as well as the wear of the needle beards, becomes more noticeable, and in machines above fifty-one gauge, it is definitely a problem.

It is accordingly an object of the present invention to provide a full-fashioned knitting machine with a needle beard pressing edge having a greater resistance to wear.

It is a further object of the invention to provide a full-fashioned knitting machine with a presser edge having increased surface contact with the beards of the needles during the beard closing action of the needles whereby wear is reduced due both to the greater area of contact and to the lower unit pressure which permits lubrication of the contacting surfaces.

As the gauge of the machines increases or becomes finer the distance between the adjacent sinkers and dividers decreases and the needle dimensions also decrease. Therefore, as these dimensions decrease, the beard of the needle becomes more flexible with a consequent tendency to be deflected out of its normal path along the presser edge at the time of the beard closing action. Actually the beard is deflected to such an extent that it engages an adjacent sinker or divider and continued deflection causes increased wear particularly at the edges of the walls forming the slots for the sinkers and dividers. Further, continued deflection of the needle beards not only causes damaging wear to the presser edge and sinker and divider slots but results in considerable beard breakage when the deflected beards catch on the knock-over bits as the needles move downwardly.

It is therefore another object of the invention to provide the sinker-head of a full-fashioned knitting machine with a presser edge adapted to maintain the needle beards against deflection during the beard closing action.

With these and other objects in view, which will become apparent from the following detailed description of the illustrative embodiment of the invention shown in

2

the accompanying drawings, my invention resides in the novel elements, features of construction and arrangement of parts in cooperative relationship as hereinafter more particularly pointed out in the claims.

5 In the drawings:

Figure 1 is a plan view of a sinker-head of a full-fashioned knitting machine having sinkers and dividers assembled therein and knitting needles between the sinkers and dividers;

10 Fig. 2 is a front elevation of the sinker-head shown in Figure 1 together with a needle bar and needles therein for cooperation with the sinker-head;

15 Fig. 3 is a fragmentary sectional view taken substantially on the line 3—3 of Fig. 2 and showing the parts on a much larger scale and in different positions relative to Fig. 2;

20 Fig. 4 is a fragmentary plan view of a portion of Fig. 1 on a scale still much larger than that of Fig. 3 and with the parts in position of Fig. 3;

25 Fig. 5 is a greatly enlarged horizontal sectional view taken through a needle beard illustrating its contact with the presser edge; and

Fig. 6 is a view similar to Fig. 5 illustrating the condition of the presser edge after a wearing in period.

30 In the drawings and description, only the means necessary to a complete understanding of the invention are specifically set forth; further information as to the construction and operation of other related, usual and well known knitting machine elements, mechanisms, etc., may be found in one or more of the following publications of the Textile Machine Works, Reading, Pa.:

The "Reading" Full-Fashioned Knitting Machine Parts Catalog, published in 1940, the supplement thereto entitled The "Reading" High Production Full-Fashioned Knitting Machine, published in 1940, and The "Reading" Full-Fashioned Knitting Machine Parts Catalog published in 1947.

Referring to the drawings more in detail, a sinker-head for a common type of full-fashioned knitting machine 40 is shown at 10. Sinker-head 10 comprises a base member or bottom 12 and a cap member or top 14 held together by bolts such as 16 and 17. Bottom 12 has apertured ears 13 by which it may be bolted to the machine frame, while top 14 has the usual verge plate 15 secured thereto 45 by screws or the like, the verge plate serving to limit and cushion the movements of the sinkers at the ends of their yarn drawing strokes. The bottom 12 is also provided with bearings 11 for pivotally supporting a bed 26 for usual knocking over bits 27 (Figs. 2 and 3). Members

50 12 and 14 are both slotted transversely of their lengthwise dimension and arranged so the slots of one member are in the same vertical planes as those in the other member when the sinker-head is in its usual horizontal position. Said slots in the bottom 12 are designated as 18 and those 55 in the top 14, as 19. Slots 18 and 19 are occupied by alternately arranged sinkers 20 and dividers 21. As appears in Figure 1, the backs of the sinkers 20 are thickened by reinforcing members so that jacks (not shown) can better deliver operative impulses thereto while the 60 dividers 21 are provided with the usual reinforcing tail portions which act to guide the jacks and keep them in alignment with their respective sinkers.

The sinker-head 10 is so mounted that the sinkers 20 and dividers 21 reciprocate horizontally in planes intermediate needles 22 which are mounted in a needle bar 25 which is so mounted and operated that the needles remain generally vertical throughout their knitting cycles. The sinkers and dividers operate while the needles 22 are at or near the upper end of their stroke to sink and 65 divide yarn to form loops around the shanks of the needles, the loops being caught under beards 23 of the needles on their downstroke. The needle beards 23 are

pressed or closed on their downstroke to carry the newly formed loops downwardly through the previously formed loops which are supported on the knockover bits 27 in the usual manner. In a full-fashioned knitting machine the needle beards 23 are closed by operating the needles to press the beards against a front edge portion 30 of the sinker-head bottom as shown in Fig. 3 to force the tip of the beard of the needle within an eye or recess 32 in the needle.

During the beard pressing action of the needles 22, particularly in the finer gauge machines, the beards, being very flimsy in structure, are deflected out of their normal vertical paths and in many instances such deflection is sufficient to cause the beards to engage the sides of adjacent sinkers and dividers. Continued deflection of the needle beards causes the beards to wear grooves in the presser edge thereby damaging the presser edge to such an extent that the beards cannot follow any but the deflected path. Also, where the beards are deflected against the sinkers or dividers, they very soon cause wear at the corner edges of the walls forming the slots 18 thereby additionally damaging the base 12 of the sinker-head 10.

One factor contributing to excessive wear of the presser edge and also to the needle beards, particularly at the initial stages of operation, is the failure to secure adequate lubrication under the pressures present when the needle beards have only point or line contact with the presser edge. For example, it has been determined that such pressures are of the order of sixteen hundred pounds or more per square inch when the needle beards, as is true at that time, have an area of contact with the presser edge only of the order of 0.0005 to 0.001 inch in width. Under such heavy unit pressures the lubricating oils as conventionally used are either squeezed out of the areas of contact or for some other reason fail to perform their normal lubricating functions.

In accordance with the instant invention the above noted difficulties are overcome by providing means located preferably centrally between the slots 18 to control the position of the needle beards and to substantially increase their area of contact with the presser edge whereby the tendency of the beards to deflect is overcome and the pressure per square inch on the needle beard and presser edge is reduced to a point where adequate lubrication is obtained. The means provided for these purposes comprises grooves 38 extending vertically of the presser edge and located intermediate the slots 18 for the sinkers and dividers as shown in Figs. 4, 5 and 6. Grooves 38 are originally of V-shape in horizontal cross-section and are formed by a milling or similar machining operation. It has been determined that the angular relationship of the sides of the grooves as well as the depths of the grooves may vary within reasonable limits but should be such that the side walls of the grooves are in tangential relationship to the needle beard and extend at a relatively wide angle to one another. Preferably an angle of the order of 135° is employed. Thus for fine gauge machines, such for example as 60-gauge machines, employing needles having beards approximating 0.007 inch in diameter, it has been found that superior results are obtained by milling the grooves to a depth of the order of 0.001 to 0.0015 inch with the sides of the groove extending at said angle of 135° to each other.

Referring specifically to Figs. 5 and 6, the former shows on a greatly enlarged scale, the manner in which the needle beard is received within a groove of the type described above. As will be readily apparent, the area of contact between the needle beard and the groove has been doubled as compared to the conventional construction. Also, the groove exerts a holding action on the needle beard to resist any tendency of the beard to de-

flect in either direction from its ideal position centrally of the space between the adjacent sinker and divider.

Furthermore, as the place of contact of the needle beard against the presser edge is definitely fixed, wearing away of the presser edge, which inevitably occurs, will cause the area of contact to gradually increase until the ideal condition disclosed in Fig. 6 is achieved. As illustrated at this time the grooves have arcuate bottom portions of a radius of curvature substantially equal to that of the needle beards and entrance portions defined by what remains, if any, of the original inclined side walls. After this point, wear will be reduced to a minimum as a substantial area of contact is then present. Even in the initial stage as illustrated in Fig. 5 and in the intermediate stages, lubrication will be greatly improved due to the great reduction of unit pressure between the needle beard and the walls of the groove.

While the transition from the relationship between the needle beard and the presser edge shown in Fig. 5 to that of Fig. 6 may take place during the normal operation of the machine, the grooves 38 may, if desired, be shaped to the configuration shown in Fig. 6 before the sinker-head is installed in the knitting machine. A suitable way of performing this operation is to install the sinker heads having grooves as shown in Fig. 5 in a special machine having needle bars carrying conventional needles and including means for operating the needle bars through the normal cycle of needle beard closing movements but at a greatly accelerated rate whereby the grooves are rapidly worn or abraded to the condition shown in Fig. 6. Thereafter the sinker-heads are installed in the knitting machines in which they are to be used. The use of suitable breaking-in oils to promote wear is particularly applicable to such operation but as will be recognized they also may be employed until the desired condition is reached in the case where the sinker-heads having the grooves illustrated in Fig. 5 are installed directly on the knitting machine.

Of course, the improvements specifically shown and described by which the above results are obtained can be changed and modified in various ways without departing from the invention herein disclosed and hereinafter claimed.

I claim:

1. In a full-fashioned knitting machine, the combination of a sinker-head comprising a base member having slots therein, sinkers and dividers in said slots, bearded needles between said slots and a stationary presser edge defined by the front face of the base member, and grooves in said presser edge extending substantially centrally between said slots and spaced therefrom to receive the beards of the needles and to hold them from contacting the sinkers and dividers.

2. A sinker-head for a full-fashioned knitting machine having sinkers, dividers and bearded needles, said sinker-head comprising a base member having slots therein to receive the sinkers and dividers, a stationary needle beard presser edge defined by the front face of the base member, and vertical grooves in said presser edge extending substantially centrally between and spaced from the slots to receive the beards of the needles and prevent deflection thereof.

3. A sinker-head for a full-fashioned knitting machine having sinkers, dividers and bearded needles, said sinker-head comprising a base member having slots therein to receive the sinkers and dividers, a stationary needle beard presser edge defined by the front face of the base member, and vertical grooves in said presser edge extending substantially centrally between and spaced from the slots to receive the beards of the needles, said grooves being of curved cross-section with a radius of curvature substantially the same as that of the needle beards.

4. A sinker-head for a full-fashioned knitting machine having sinkers, dividers and bearded needles, said sinker-head comprising a base member having slots therein to

receive the sinkers and dividers, a needle beard presser edge defined by the front face of the base member, and vertical grooves in and extending for the entire height of said presser edge substantially centrally between and spaced from the slots to receive the needle beards, said grooves being of an initial V-shape in cross section with their side walls tangent to the needle beards when in contact therewith.

5. A sinker-head for a full-fashioned knitting machine having sinkers, dividers and bearded needles, said sinker-head comprising a base member having slots therein to receive the sinkers and dividers, a needle beard presser edge defined by the front face of the base member, and vertical grooves in said presser edge substantially centrally between and spaced from the slots to receive the needle beards, said grooves being of an initial V-shape in cross-section with the side walls of the grooves lying at an angle of the order of 135° to each other and said side walls lying in tangential relationship to the needle beards when in contact therewith.

6. A sinker-head for a full-fashioned knitting machine having sinkers, dividers and bearded needles, said sinker-head comprising a base member having slots therein to receive the sinkers and dividers, a needle beard presser edge defined by the front face of the base member, and vertical grooves in said presser edge substantially centrally between and spaced from the slots to receive the needle

beards, said grooves being of initial V-shape in cross-section and of the order of 0.001 to 0.0015 inch in depth with their side walls lying at an angle of the order of 135° to each other and with said side walls lying in tangential relationship to said needle beards when in contact therewith.

7. A sinker-head for a full-fashioned knitting machine having sinkers, dividers and bearded needles, said sinker-head comprising a base member having slots therein to receive the sinkers and dividers, a needle beard presser edge defined by the front face of the base member, and vertical grooves in said presser edge extending substantially centrally between and spaced from the slots to receive the needle beards, said grooves having an arcuate bottom portion of a radius of curvature substantially equal to that of the needle beards.
